CLAIM

The ornamental design for a LED infrared skin-treatment device, as shown and described.

DESCRIPTION

FIG. 1 is a front-elevational view of the LED infrared skin-treatment device showing my new invention;

FIG. 2 is a rear-elevational view thereof;

FIG. 3 is a right-side elevational view thereof;

FIG. 4 is a left-side elevational view thereof;

FIG. 5 is a perspective view thereof;

FIG. 6 is an enlarged bottom-plan view thereof; and,

FIG. 7 is an enlarged top-plan view thereof.

The dashed lines show portions of the LED infrared skin-treatment device which form no part of the claimed design.
